HYDRAULIC SPEED CONTROL
GOVERNOR

Bert G. Carlson, Gates Mills, Ohio, assignor, by
mesne assignments, to Jack & Heintz Precision
Industries, Inc., Cleveland, Ohio, a corporation
of Delaware

Application April 26, 1945, Serial No. 590,408

5 Claims. (Cl. 264—19)

1

This invention relates in general to speed control governors and more particularly to improvements in hydraulic speed control governors and has for one of its primary objects to provide a simple and efficient self-contained unit which will maintain a constant speed of the prime mover by automatically adjusting the same and eliminate vibrations by effectively dampening vibrations due to sudden load changes without involving a loss of energy due to heat or equilibrium speed of the governor.

Another paramount object is to provide an hydraulic speed control governor which by its construction including a rotating impeller driven by the prime mover and a spaced and opposed spring loaded and damped non-rotative axially reciprocable shell provides for the virtual elimination of friction and efficiency losses resulting therefrom.

A further object is to provide such a governor that will provide for the heat exchange between the disturbed hydraulic fluid and static cooling hydraulic fluid.

With the foregoing and other objects in view, the invention resides in the new and novel process and resulting construction hereinafter set forth in the following specification and appended claims, certain embodiments thereof being illustrated in the accompanying drawings, in which:

Figure 1 is a view in longitudinal section taken through the hydraulic speed control governor units;

Figure 2 is a view in section taken along line 2—2 of Figure 1;

Figure 3 is a view in section taken along line 3—3 of Figure 1; showing the rotating impeller in top plan view; and

Figure 4 is a view in section taken along line 4—4 of Figure 1, showing the reciprocable shell in bottom plan view.

Referring more particularly to the drawings, the unit includes a housing 1 with a detachable cap 2. The impeller 3 is rotatably mounted in housing 2 by a ball bearing assembly including ball bearings 4 and inner and outer races 5 and 6. Impeller 3 may be provided with a removable drive shaft 7, of square or angular cross section, and having a bevelled groove head 8 to receive a snap ring retainer 9 which engages the head to retain the latter in driving engagement with the impeller. Above the drive shaft is an oil seal disc 10 and below the ball bearing assembly and against the inner surface of the housing is a soft material oil seal 11 and an oil seal washer 12 therefor. Below this and about the

2

impeller is a soft material oil seal 13 between two oil seal washers 14 and 15 below which is provided a retaining ring 16.

The impeller itself is formed to have a semi-circular cavity 17 divided into a plurality of cavities by spaced vanes 18 therein and to which latter is secured a continuous circular flat ring 19 intermediate the inner and outer extremities of the vanes. As stated before, the load of the rotation of the impeller is borne by the ball bearing assemblies including the balls 4 and the races 5 and 6.

Opposed to and spaced longitudinally of the impeller is a shell 20 that is engaged by a screw 15 bolt 21 to secure the shell to a reciprocating guide shaft 22 slidably mounted in bushing 23 that is rotatably mounted in housing cap 2. Bushing 23 is externally screw threaded to receive a nut 24 between which and the shell 20 is disposed a compression coil spring 25 that surrounds the bushing and the slidable shaft. The nut 24 has a slot to receive a guide pin 26 that is carried by the housing cap. Secured rigidly to bushing 23 is a speed adjustment dial 27 the turning 20 of which in either direction causes the nut 24, which is restricted against rotation by guide pin 26, to ride up or down on the bushing and thus decrease or increase the compression of coil spring 25 accordingly.

30 The shell 20 is formed to have a cavity 28 opposed to cavities 17 of the impeller, the outer extremity of the shell having a depending circular flange 29 extending with clearance into an annular chamber 30 in the housing that extends 35 below the head of the impeller. Surrounding shaft 22 and bushing 23 is a longitudinally expandable bellows 31 of the type known in the trade as a "Sylphon." This "Sylphon" is secured to the housing cap by pins 32 and to the shell 20 by pins 33. The shell 20 is provided with a circular series of spaced apertures 34 in its dished portion and a circular series of spaced apertures 35 in its central flat portion.

40 The chamber provided by the housing and its cap may be filled with oil or other hydraulic fluid to a level appreciably higher than that of shell 20 so as to fill chamber 30 and part of the interior, as well as exterior, of bellows 31. The resistance which the fluid in cavities 17 of the rotating impeller offers to the rotating vanes 18 thereof as the vanes take the fluid along with a fraction of their angular velocity creates a force which is transferred to and resisted by shell 20 as it is reciprocated against the action of coil spring 25 45 whose compression is adjustable by speed dial 21.

The action of the impeller with its vanes 18 and flat band 19 in the fluid in which it is submerged is the same as that of the impeller of a fluid coupling. The construction of the shell 20 with its opposed cavity 23 and overhanging flange 29 is such as to receive the hydraulic fluid disturbed and deflected by the impeller in such a manner as to enable the shell to remain centrally balanced in its reciprocation against the action of spring 25 and in response to the hydraulic force set up by the impeller. The hydraulic fluid having access to the interior and exterior of the bellows 31 renders the latter capable of effectively dampening the reciprocating movements of the shell and particularly the dampening of vibrations that would otherwise be present in case of sudden load changes. By means of the simple adjustment of speed adjustment disc 27 a normal adjustment of the governor may be made for purposes of controlling the speed of the prime mover by increasing the compression of spring 25 to lessen the top speed and by decreasing such compression to increase the top speed. Besides the greater hydraulic force exerted vertically upwardly from the cavities of the impeller a centrifugal force is also exerted at an angle approximately equal to that of the inclination of the angular inner surface 36 of shell 20. This surface 36 deflects the oil inwardly where it drops down into cavities 17 of the impeller. The apertures 34 act as breathers and as a means for eliminating air bubbles when the unit is filled with hydraulic fluid. It will be appreciated that the main disturbance of oil occurs in the impeller and that the area of such disturbance is restricted to the chamber formed by the opposed faces of the impeller and shell. Hence the remainder of oil in the unit above the shell is static and acts effectively as a cooling medium by ready heat exchange between the static oil and the disturbed oil. Positive provision is made for this heat exchange feature in that the hydraulic fluid in the chamber formed by the opposed faces of the impeller and shell is forced upwardly through the breather holes 34 to circulate with the static cooling fluid above the shell where it may then be forced downwardly in chamber 33 around the shell flange 29 and back into the cavities 17 of the impeller.

I claim:

1. An hydraulic speed control governor comprising an housing to contain hydraulic fluid, a prime mover driven rotating impeller submerged in said fluid and being of bowl formation to provide a cavity divided by spaced vanes and a flat circular ring secured to said vanes intermediate their inner and outer extremities, a shell submerged in said fluid and having a concave surface disposed to be opposed to that of said impeller and carried by a shaft reciprocably mounted in said housing, said shell being adapted to resist by reciprocation the hydraulic forces set up by the fluid disturbed by the rotation of said impeller, an expansible bellows secured to said housing and to said shell and partially submerged exteriorly and interiorly in said fluid and adapted to dampen vibrations transmitted to said shell and housing by the rotation of said spaced impeller.

2. An hydraulic speed control governor comprising an housing to contain hydraulic fluid, a prime mover driven rotating impeller submerged in said fluid and being of bowl formation to provide a cavity divided by spaced vanes and a flat circular ring secured to said vanes intermediate their inner and outer extremities, a shell sub-

merged in said fluid and having a concave surface disposed to be opposed to that of said impeller and carried by a shaft reciprocably mounted in said housing, said shell being adapted to resist by reciprocation the hydraulic forces set up by the fluid disturbed by the rotation of said impeller, spring and stop means for normally maintaining said shell and impeller in a predetermined spaced relationship, said shell being adapted to resist by reciprocation against the action of said spring the hydraulic forces set up by the fluid disturbed by the rotation of said impeller, an expansible bellows secured to said housing and to said shell and partially submerged exteriorly and interiorly in said fluid and adapted to dampen vibrations transmitted to said shell and housing by the rotation of said spaced impeller.

3. An hydraulic speed control governor comprising an housing to contain hydraulic fluid, a prime mover driven rotating impeller submerged in said fluid and being of bowl formation to provide a cavity divided by spaced vanes and a flat circular ring secured to said vanes intermediate their inner and outer extremities, a shell submerged in said fluid and having a concave surface disposed to be opposed to that of said impeller and carried by a shaft reciprocably mounted in said housing, said shell being adapted to resist by reciprocation the hydraulic forces set up by the fluid disturbed by the rotation of said impeller, spring and stop means for normally maintaining said shell and impeller in a predetermined spaced relationship, said shell being adapted to resist by reciprocation against the action of said spring the hydraulic forces set up by the fluid disturbed by the rotation of said impeller, means for adjusting the resisting force of said spring for adjusting the speed limits of said governor, an expansible bellows secured to said housing and to said shell and partially submerged exteriorly and interiorly in said fluid and adapted to dampen vibrations transmitted to said shell and housing by the rotation of said spaced impeller.

4. An hydraulic speed control governor comprising an housing to contain hydraulic fluid, a prime mover driven rotating impeller submerged in said fluid and being of bowl formation to provide a cavity divided by spaced vanes and a flat circular ring secured to said vanes intermediate their inner and outer extremities, a shell submerged in said fluid and having a concave surface disposed to be opposed to that of said impeller and carried by a shaft reciprocably mounted in said housing, a bushing rotatably mounted in said housing and adapted to slidably receive said shaft, said shell being adapted to resist by reciprocation the hydraulic forces set up by the fluid disturbed by the rotation of said impeller, an expansible bellows secured to said housing and to said shell and partially submerged exteriorly and interiorly in said fluid and adapted to dampen vibrations transmitted to said shell and housing by the rotation of said spaced impeller.

5. An hydraulic speed control governor comprising an housing to contain hydraulic fluid, a prime mover driven rotating impeller submerged in said fluid and being of bowl formation to provide a cavity divided by spaced vanes and a flat circular ring secured to said vanes intermediate their inner and outer extremities, a shell submerged in said fluid and having a concave surface disposed to be opposed to that of said impeller and carried by a shaft reciprocably mounted in said housing, a bushing rotatably mounted

in said housing and adapted to slidably receive said shaft, said shell being adapted to resist by reciprocation the hydraulic forces set up by the fluid disturbed by the rotation of said impeller, an expansible bellows secured to said housing and to said shell and partially submerged exteriorly and interiorly in said fluid and adapted to dampen vibrations transmitted to said shell and housing by the rotation of said spaced impeller, said bushing carrying a non-rotative follower nut, a com-

pression coil spring surrounding said shaft and held between said nut and said shell and manual means on said bushing for turning the latter to operate said follower nut to adjust the compression of said spring and the consequent resistance of said shell to reciprocation under the hydraulic influence of the fluid disturbed by the rotation of said impeller.

BERT G. CARLSON.
